PASSAGE TYPE DRAWING FRAME FOR SPINNING FIBERS OF VARIOUS STAPLE DIMENSIONS

Hermann Kluftinger, Augsburg, Germany

Application February 24, 1937, Serial No. 127,386
In Germany February 8, 1936

14 Claims. (Cl. 19—131)

The present invention relates to drawing frames for spinning fibers, and has for its object to provide an organization which is adjustable for various staple lengths.

5 Another object of the invention is to provide an arrangement whereby a drawing frame of the gripping type may be changed to a drawing frame of the passage type and vice versa without requiring fundamental alterations of the drawing frame structure.

10 A further object of the invention is to provide means in a drawing frame of the said type for preventing a stopping of the entire machine in the event of a lap formed around the front roller.

15 The invention broadly consists in means for positively driving a belt or sleeve as used in machines of the said type for feeding the roving to a pair of front drawing rollers, and in means for adjusting the distance of such belt drive from 20 said front rollers. Said means comprise a removably insertable member in the roller stand between the lower front drawing roller and the driving roller of said belt, said means being so shaped as to form the bearings for elements such

25 as needle rollers having the purpose of guiding, deflecting and or tensioning the belt. In certain embodiments of the invention two members of the mentioned type are rigidly connected by a bar-shaped part, whereby said two members may be 30 inserted in two coordinated roller stands, said bar-shaped part bridging the roller stands and safeguarding the parallelism of the needle rollers with the drawing rollers. The arrangement offers the additional advantage that, for the belt drive, 35 no weighting or pressure rollers are required which have been found objectionable in many instances. Small and light rollers may be present in connection with the belt to aid the forwarding of the roving to the front rollers.

40 Further details and objects of my invention appear from the description hereinafter and the accompanying drawings illustrating embodiments of the invention by way of example and in which

Fig. 1 is a side view of a drawing frame,

45 Fig. 2 is a side view of slightly modified parts of the drawing frame on a larger scale.

Fig. 3 is a front view of the parts shown in Fig. 2,

50 Fig. 4 is a sectional view along the line IV—IV of Fig. 3,

Fig. 5 is a sectional view along line V—V of Fig. 3,

55 Fig. 6 shows a modified drawing frame according to the present invention, the small leather belt being particularly long.

Fig. 7 is a sectional view of a detail of the modification illustrated in Fig. 6.

Fig. 8 shows another modification,

Fig. 9 is a front view, and Fig. 10 is a side view of a detail of the modification shown in Fig. 8,

5 Fig. 11 is a section along the line XI—XI of the Fig. 9,

Figs. 12, 13 and 14 illustrate several possibilities of adjustment,

Fig. 15 is a side view of the deflector needle 10 roller.

Referring now to Fig. 1, rollers or cylinders I, II and III are supported by two roller stands 1. The front cylinder I has a fixed bearing in each stand, whereas the cylinders II and III are journaled in sleds or carriages 2 displaceable lengthwise on said roller stands. This arrangement allows to move the sleds 2 back and forth, in the direction of the arrow A. At the front end of the guide provided for this purpose in each roller stand 1, there is a notch or recess 3 in the front wall 20 of which serves as a stop for the sled in its forward end position. Rollers IV, V and VI are provided on top of rollers I, II and III respectively, 25 roller IV being an upper drawing roller coordinated to the lower drawing roller I, and roller V being a feeding roller to cooperate with the feeding belt 11. Said belt or hose 11 is passed around middle roller II which serves as the driving roller for said belt. The belt forms a moving board for 30 feeding the roving from roller III to roller I. Means are provided for guiding and tensioning belt 11 and for simultaneously deflecting it in such a manner that a large arc of contact at roller 35 II and, thus, an absolutely positive drive of the belt is safeguarded. In the illustrated embodiment, said means comprise a bar-like member 5 having at its ends two base plates 4. The bar with its base plates forms a substantially U-shaped unit. The base plates are recessed in relation to the main portion of bar 5, and may be inserted into the recesses 3 of two roller stands 1 respectively, the bars fitting in between said roller stands and bearing against them with their flank portions 30 below the base plates 4. Thus, bar 5 40 may be held in true parallelism with rollers I, II, III, and the base plates at right angles thereto. Insertion of the base plates in the recesses 3 may be accomplished when the sleds are withdrawn in the direction of arrow A.

In the middle of bar 5, a support 6 may be provided. The base plates 4 and support 6 contain bearings formed by half-round recesses 7 and 8 for rollers or needles 9 and 10. The needles have smooth surfaces and small diameters, 50

and may be freely placed into the bearing recesses 7 and 8. The width of a base plate 4 may equal the width of its coordinated recess 3, and it is obvious that the tension of the belt depends upon the location of the bearing recesses for the needles in the base plates, and the diameter of the needles journalled therein. Since the base plates are exchangeably inserted in the roller stands, suitable conditions of the belt drive 10 can be obtained in each instance.

In order, however, to facilitate the adjustment, I prefer to make the recesses 3 wider than the base plates 4 as clearly shown in Fig. 2. In this figure sled 2 is retracted and the base plate 4 and needles 9 and 10 are inserted preparatory to the tensioning of belt 11. The base plate is in a rearwardly slanting position. When sled 2 is shifted from the position of Fig. 2 in a forward direction indicated by arrow B, it engages base plate 4 which will be swung and erected in the way indicated by arrow C under the action of the forward movement of the sled. At the same time the roller 10 engages the leather belt 11 in the direction of the arrow D. Thereby the arc of engagement of the belt with the middle cylinder II will be increased a certain extent, and the leather belt will be correspondingly tensioned. In consequence thereof, the drive of the belt is absolutely positive without requiring weighting rollers or the like to safeguard a constant and uniform movement of the belt. The arrangement of the needle 9 near the front edges of the base plates permits to extend the moving board formed by the belt, very close 35 to the front drawing roller or cylinder I.

Although the rollers 9 and 10 are not completely encompassed by closed bearings, they are safely retained in position as they are held and guided by adjacent parts such as the roller 40 stands, the sleds and the leather belt.

On the other hand, a lap accidentally formed about cylinder I will lift needle 9 out of its bearing recesses, thus interrupting the action of the belt without stopping or disturbing the operation 45 of other parts of the machine. Similarly, the tension of the belt may be released during intermissions of the operation, by shortly reversing the machine whereby needle 9 is caused to leave its bearing recesses 7.

If the leather belt drawing frame described hereinbefore is to be changed into a gripping type drawing frame, the reverse order of operation is to be followed. The sleds 2 are to be withdrawn, and the belt and the bar with the 50 base plates removed. This being done, the drawing frame mechanism may be adjusted and operated as a conventional gripping type drawing frame. Thus, the present invention offers means for transforming a gripping type drawing frame 55 into a belt type drawing frame and vice versa, without any basic changes of structural characteristics.

In the event that an especially long leather belt is to be used, the upper part of the base 60 plate may have a correspondingly wide extension. This is shown in Fig. 6, where the belt is denoted with 111, said extension with 120, and said base plate proper with 104. In this case, a supporting board or table 12 may be inserted 65 into the base plates for cooperation with a top roller 13. The leather hose or belt is held in position between said table 12 and said roller 13, although it may have a slight slack at 14 (see Fig. 7) owing to the absence of tension between 70 the lower roller II and the top roller 13.

In order to obtain an elastic pressure, it is advisable to apply resilient means for deflecting and or tensioning the belt. If this is done, the resilient system will take up at least some of the elongations of the leather belt. In the embodiment of Figs. 8 to 11, a leaf spring 15 is used for this purpose instead of the said tensioning needle 10, shown in Figs. 1, 2, 6 and 7. The leaf spring is attached to the base plate bar 205 in such a manner that it resiliently bears against the belt in the direction of the belt motion. At its end 16, the leaf spring is appropriately curled, the spiral end engaging the small leather hose. As shown in Figs. 8 and 10, the base plate 204 may have a recess 240 in addition to recess 208 15 for needle 9. Recess 240 is provided in the top portion of plate 204 and serves to accommodate a roller 250 cooperating with the belt to feed the roving to the front drawing rollers.

In the drawing frame, according to my invention, means may be provided to adjust various distances of the rollers without requiring essential structural changes of the machine. Such means may consist in shims applied in connection with said base plates, as illustrated by Figs. 12 to 14. A shim 17 inserted in front of the base plate enlarges the main drawing range, increases the distance C and simultaneously the distance D between the leather belt deflecting roller 9 and the gripping point of the front cylinder I. 30

By placing a shim or liner 18 behind the base plate, an increase of the main drawing range may be obtained, i. e., the distance C between the front cylinder and the middle cylinder will be increased without alteration of the distance D between the gripping point of the front cylinder I and the needle 9. Simultaneously the board formed by the leather belt 11 will be lengthened.

A simultaneous insertion of shims 17 and 18 40 results in an increase of the total drawing range, at the same time the distances C, D and E being modified. A drawing frame according to my invention may be advantageously used in the spinning of fibrous materials of various staple 45 lengths. It is particularly useful in the spinning of long stapled material together with short staples. Owing to the absolutely positive drive of the belt in the absence of weighting rollers, the belt is advanced with a very constant speed necessary to safeguard the forwarding of uniform 50 quantities of the roving to the front drawing cylinders.

Having now particularly described and ascertained the nature of my said invention and in 55 what manner the same is to be performed, I declare that what I claim is:

1. In a drawing frame for spinning fibers, the combination of two roller stands in parallel arrangement, drawing means including a lower 60 drawing roller, a lower driving roller, a feeding belt passing around said driving roller, a feeding roller cooperating with the upper run of said belt, a member comprising a bar-like main portion and two end portions, said end portions being 65 removably mounted in said roller stands respectively between said lower drawing roller and said lower driving roller, means in connection with said end portions for guiding said belt in operative relation to said lower drawing roller, and 70 other means in connection with said member and in engagement with the lower run of said belt for deflecting said belt to increase its arc of engagement with said driving roller.

2. A device as claimed in claim 1 in which the 75

end portions of said member include surfaces perpendicular to the length of the main portion of said member, said surfaces being adapted to bear laterally against said roller stands to safe-
5 guard parallelism of said member with said rollers.

3. In a drawing frame for spinning fibers, the combination of a roller stand, drawing means including a lower drawing roller, a driving roller, 10 a feeding belt passing around said driving roller, a feeding roller cooperating with said belt, a member removably inserted in said roller stand between said drawing roller and said driving roller, said member having a first recess in its front 15 top portion and a second recess in its rear portion, said recesses being open towards the front and top and towards the rear side respectively, a needle roller in said first recess for guiding said belt in operative relation to said drawing roller, 20 and another needle roller in said second recess for deflecting said belt to increase its arc of engagement with said driving roller.

4. In a drawing frame for spinning fibers, the combination of a roller stand, drawing means including a lower front drawing roller journaled in said stand, a sled movable behind and in a direction at right angles to said drawing roller, 25 said roller stand including guiding means for said sled and having a recess between said drawing roller and said guiding means, a driving roller journaled in said sled, a feeding belt passing around said driving roller, a feeding roller cooperating with said belt, a member inserted in said 30 recess, the width of said member being smaller than that of said recess, a needle roller journaled at the front top portion of said member for guiding said belt in operative relation to said drawing roller, and a means in connection with said 35 member at a lower level than and in the rear of said needle roller, said means being adapted to engage said belt from below, whereby said belt can be deflected to increase its arc of engagement with said driving roller when said member is tilted from a rearwardly slanting into an erected 40 45 position.

5. A device as claimed in claim 4 in which said member includes a portion protruding into the path of said sled when the member is inserted into said recess, whereby said member may be 50 erected from a rearwardly slanting position by a forward movement of said sled.

6. In a drawing frame for spinning fibers, the combination of a roller stand, drawing means including a lower drawing roller journaled in the 55 front portion of said roller stand, a driving roller in the rear of said drawing roller, a feeding belt passing around said driving roller, a member removably inserted in said roller stand between said drawing roller and said driving roller, said 60 member having a rearward extension, a needle roller journaled at the front top portion of said member to guide said belt in operative relation to said drawing roller, means at the rear end of said extension for deflecting said belt to increase 65 its arc of contact with said driving roller, a board removably inserted in the top of said extension to support said belt, and a cooperating roller on top of the belt portion supported by said board.

7. In a drawing frame for spinning fibers, the 70 combination of a roller stand, drawing means including a lower drawing roller journaled in the front portion of said roller stand, a lower driving roller in the rear of said drawing roller, a feeding belt passing around said driving roller, 75 an upper feeding roller in operative relation to

said belt near said driving roller, a member removably mounted in said roller stand between said lower drawing roller and said lower driving roller, a needle roller journaled in the front top portion of said member for guiding said belt in 5 operative relation to said drawing roller, means in connection with said member for deflecting said belt to increase its arc of engagement with said driving roller, and another roller journaled on the top of said member, said other roller being 10 adapted to bear upon said belt from the upper outside near said drawing roller.

8. In a drawing frame for spinning fibers, the combination of two roller stands in parallel arrangement, drawing means including a lower 15 drawing roller and a driving roller journaled therein, a feeding belt passing around said driving roller, a feeding roller cooperating with said belt, a member comprising a bar-like middle portion and two end portions, said end portions being removably inserted in said roller stands respectively between said drawing roller and said driving roller, said bar-like portion including a projection between said roller stands, a guiding roller journaled in both said end portions and 20 in said projection to hold said belt in operative relation to said drawing roller, and means in connection with said end portions for deflecting said belt to increase its arc of engagement with 25 said driving roller.

9. In a drawing frame for spinning fibers, the combination of a roller stand, drawing means including a lower drawing roller journaled in the front portion of said roller stand, a lower driving roller in the rear of said drawing roller, a feeding belt passing around said drawing roller, a feeding roller cooperating with said belt said 30 roller stand having a recess between said lower drawing roller and said driving roller, a member removably mounted in said recess of the roller stand between said drawing roller and said driving roller, a needle roller removably inserted and journaled in the front portion of said member for guiding said belt from the inside near said 35 drawing roller, and resilient means in connection with said member and engaging the belt from its lower outside for deflecting said belt to increase 40 its arc of engagement with said driving roller.

10. In a drawing frame for spinning fibers, the combination of two roller stands in parallel arrangement, drawing means including a lower drawing roller journaled in the front portions of said roller stands, a driving roller in the rear of said drawing roller, a feeding belt passing around said driving roller cooperating with said belt, a member comprising a main portion and two end portions, said end portions being removably inserted in said roller stands respectively between said drawing roller and said driving roller, a needle roller journaled in the top front 55 portions of said member to guide said belt from the inside near said drawing roller, and a leaf spring secured to the main portion of said member, the free end of said spring being adapted to bear against the lower outside of said belt 60 in the direction of its movement, so as to deflect the belt to increase its arc of engagement with said driving roller.

11. In a drawing frame for spinning fibers, the combination of a roller stand, drawing means 70 including a lower drawing roller journaled in the front portion of said roller stand, a driving roller in the rear of said drawing roller, means for adjusting the distance between said drawing roller and said driving roller, said roller stand 75

- 5 having a recess between said rollers, a feeding belt passing around said driving roller, a feeding roller cooperating with said belt, a member inserted in said recess, the width of said member being smaller than that of said recess, a needle roller journaled at the front portion of said member to guide said belt from the inside near said drawing roller, means in connection with said member for deflecting said belt to increase its arc of engagement with said driving roller, and shims insertable in said recess for adjusting the position of said member relatively to said drawing and said driving rollers.
- 10 12. In a drawing frame for spinning fibers, the combination of a roller stand, drawing means including a lower drawing roller, a driving roller, a feeding belt passing around said driving roller, a feeding roller cooperating with said belt, said roller stand having a recess between said lower drawing roller and said driving roller, a member removably supported in said recess of the roller stand, said member having a recess in its top portion, means carried by said member in said recess of its top portion for guiding said belt in operative relation to said drawing roller, whereby said means with said belt may be lifted out of engagement with said member, and other means carried by said member and being in engagement with the lower run of the belt for deflecting said belt to increase its arc of engagement with said driving roller.
- 15 14. In a drawing frame for spinning fibers, the combination of a roller stand, drawing means including a lower drawing roller, a driving roller, said roller stand having a recess between said lower drawing roller and said driving roller, a feeding belt passing around said driving roller, a feeding roller cooperating with said belt, a member removably supported in said recess of said roller stand, said member having another recess in its front top portion near said drawing roller, a needle roller inserted in said last-mentioned recess to guide said belt in operative relation to said drawing roller, said last-mentioned recess being open towards the top and so constructed and arranged that the pull of the belt tends to urge said needle roller into said last-mentioned recess when the belt is moving in the operative direction and that a force occurring when the belt is moving in the opposite direction tends to lift the needle roller out of said last-mentioned recess, and means in connection with said member for deflecting said belt to increase its arc of engagement with said driving roller.
- 20 15. In a drawing frame for spinning fibers, the combination of a roller stand, drawing means including a lower drawing roller, a driving roller, a feeding belt passing around said driving roller, a feeding roller cooperating with said belt, a member removably supported in said recess of the roller stand, said member having a recess in its top portion, means carried by said member in said recess of its top portion for guiding said belt in operative relation to said drawing roller, whereby said means with said belt may be lifted out of engagement with said member, and other means carried by said member and being in engagement with the lower run of the belt for deflecting said belt to increase its arc of engagement with said driving roller.
- 25 16. In a drawing frame for spinning fibers, the combination of a roller stand, drawing means including a lower front drawing roller journaled in said stand, a sled movable behind and in a direction at right angles to said drawing roller, said roller stand including guiding means for said sled and having a recess between said drawing roller and said guiding means, a driving roller
